UNITED STATES PATENT OFFICE

167,188

DESK OR SIMILAR ARTICLE

Lawrence E. Blazey, Bay Village, Ohio, assignor
to Republic Steel Corporation, Cleveland, Ohio,
a corporation of New Jersey

Application October 3, 1950, Serial No. 12,431

Term of patent 14 years

(Cl. D33—7)

To all whom it may concern:

Be it known that I, Lawrence E. Blazey, a citizen of the United States of America, residing in Bay Village, in the county of Cuyahoga and State of Ohio, have invented a new, original, and ornamental Design for a Desk or Similar Article, of which the following is a specification, reference being had to the accompanying drawing, forming a part thereof, wherein:

Fig. 1 is a front elevation of a desk embodying my new design;

Fig. 2 is a front perspective view thereof;

Fig. 3 is a rear perspective view thereof; and

Fig. 4 is a side elevation thereof.

I claim:

The ornamental design for a desk or similar article, substantially as shown.

LAWRENCE E. BLAZEY.
